United States Patent Office.

SAMUEL LEMON, JR., OF HOBOKEN, NEW JERSEY, ASSIGNOR TO HIMSELF
AND CHARLES WOODRUFF, OF HUNTER'S POINT, NEW YORK.

Letters Patent No. 67,438, dated August 6, 1867.

IMPROVEMENT IN LUBRICATORS.

The Schedule referred to in these Letters Patent and making part of the same.

TO ALL WHOM IT MAY CONCERN:

Be it known that I, SAMUEL LEMON, Jr., of Hoboken, Hudson county, New Jersey, have invented a new and improved Lubricator; and I do hereby declare that the following is a full, clear, and exact description thereof, which will enable others skilled in the art to make and use the same, reference being had to the accompanying drawings, forming part of this specification.

This invention consists in arranging a rod with a valve upon it in a lubricating globe or vessel, in such a manner that the quantity of oil which is allowed to pass into the bearing or journal can be regulated with the greatest exactness by the rod from its upper end.

The drawing represents a vertical central section of the lubricator.

A is the globe or vessel which contains the oil. B is a tube, to which the globe is attached. C is the rod which passes through the cap and globe, and down into the tube B. D is the cap which screws on to the neck of a globular ring, D', which is secured to the top of the globe A, as seen in the drawing. The tube B is attached to the cross-head or pitman of a steam engine, or in any other situation where it may be desired to use a lubricator, by the screw or lower end a. The upper end of this tube passes up into the globe. There is a recess or annular groove at e, around the body of the tube, into which the lower portion of the globe fits. d represents packing under the globe and in the groove. e is a nut which screws on to the top of the tube B, and which fastens the globe to the tube, as seen. f is a conical valve on the rod c, the seat of which valve is the top of the tube.

The rod is operated or raised and lowered by taking hold of the ball g on its upper ends, and there is sufficient friction on the rod, where it passes through the cap and ring D', to keep it in place after the valve has been so adjusted by the rod that the desired quantity of oil is discharged from the globe through the tube. Around the sides of the nut e there is a chamber, h, where all sediment from the oil will be deposited. The globe A is glass; the tube and other fittings may be of brass or other suitable metal.

What I claim and desire to secure by Letters Patent, is—

The combination and arrangement of the globe A, tube B, nut e, rod c, with valve f, and caps D D', substantially as described for the purpose specified.

The above specification of my invention signed by me this 10th day of April, 1867.

SAMUEL LEMON, JR.
